UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

DRAFT RIGGING.

Application filed December 30, 1921. Serial No. 525,875.

To all whom it may concern:

Be it known that I, DONALD S. BARROWS, a citizen of the United States, residing at Rochester, in the county of Monroe and 5 State of New York, have invented certain new and useful Improvements in Draft Rigging; and I do hereby declare the following to be a full, clear, and exact description of the invention, such as will enable others 10 skilled in the art to which it appertains to make and use the same.

The invention relates to draft rigging for railway cars and more particularly to a stop member adapted to cooperate with a 15 horizontally arranged yoke, said stop member being adapted to fit between the draft or center sills to connect the same rigidly and to provide a tie member to prevent the said sills from spreading.

20 The principal object of my invention, generally considered, is to provide a unitary metallic back stop having its end walls, webs, and flanges arranged and disposed so as to economically distribute the metal to thereby 25 produce a casting which is of great strength yet light in weight.

Another object of my invention is to provide a back stop casting in which the buffing face is adequately braced so as to effectively 30 resist all buffing stresses to which the same may be subjected and to distribute the stresses throughout the casting to best advantage.

To this end the primary feature of the 35 invention, generally stated, comprises the formation of a back stop casting constructed of a substantially I-beam section to provide a casting of uniform strength.

Another feature of my invention is to 40 provide a box-shaped casting having the transverse connecting web sloping downwardly and outwardly from the longitudinal center line thereof so as to provide maximum strength without materially increasing 45 the height of the side walls and yet at the same time providing adequate riveting area in the side walls.

Other features of the invention will be 50 pointed out in detail of the following description of the particular embodiment of my invention which has been chosen for the purpose of illustration.

In the drawings:—

Figure 1 is a top plan view of a back

stop casting constructed in accordance with 55 my invention.

Figure 2 is a side elevation of the construction shown in Figure 1.

Figure 3 is a transverse sectional view 60 taken on line 3—3 of Figure 2, the direction of view being indicated by the arrows at the ends of said section line.

Figure 4 is a view in elevation of the inner or rear end of the casting.

Figure 5 is a longitudinal section taken 65 on line 5—5 of Figure 1 and looking in the direction indicated by the arrows adjacent the ends of said section line.

The numeral 1 designates the casting generally, which is provided with a front 70 wall or flange 2, a rear wall or flange 3, a plurality of side walls 4, and a connecting web 5 preferably integrally united with the side and end walls, as clearly shown in Figure 1. The front wall 2 is preferably 75 formed with an inwardly extending intermediate portion 6 so as to conform to the rear end of the ordinary horizontal yoke 7, shown in dot and dash lines in Figure 1. The side walls are suitably perforated, as 80 at 8, to provide openings for the sill attaching rivets 9 shown in Figure 3.

The rear portions of the lower side walls are preferably offset, as at 10, from the vertical planes of the side walls so as to provide 85 pockets or recesses 11 to receive the web portions of the center or draft sill reinforcing means 12.

The transverse web 5 is preferably in the form of an inverted V having its central 90 portion at higher elevation than the portions thereof which are joined to the side walls

4. By so forming the transverse web it is possible to provide a double row of rivet openings above the web in the side walls and a single row of rivet openings below the web. Since the casting is not provided with either a cover or floor plate, it will be observed that these rivet openings are respectively accessible from the top and bottom 100 of the casting which is of great advantage in driving rivets and in inspection of the device when in service. It will be observed

that the web 5 intersects the buffing face 2 of the casting on the longitudinal center line thereof at approximately the central point of the said web or end wall 2. The rear wall 3 of the stop casting is preferably 105

arranged at a higher elevation than the front or outer wall, as clearly shown in Figure 5. By this construction, interference between the end wall 3 and the sill 5 reinforcing angles 12 is avoided and the same end wall is raised above and out of line with the usual center bearing plate with which railway cars are provided. The transverse web, it will be observed, intersects the rear wall 3 at the side edges thereof approximately in line with the bottom edge of this rear wall.

To further increase the rigidity of the web 5 and the end walls 2 and 3, I provide a longitudinally extending flange 13 which extends above and below the said web 5 and which, by means of fillets 14, extends the full height of the end walls 2 and 3. Further reinforcing means may be provided, if desired, in the shape of triangular fillets or flanges 15. As illustrated in the drawing, I provide four sets of these fillets, two being arranged to connect the upper portion of the web 2 with the web 5, two being arranged, preferably in alignment with the upper two respectively, to connect the lower face of the web 5 with the web 2, and a corresponding arrangement is provided at the rear of the casting, as clearly shown on the drawings.

In the particular embodiment of my invention, as here illustrated, it will be observed that the section modulus which resists the buffing shocks transmitted from the draft rigging cushioning elements and from the coupler when these shocks exceed the capacity of the cushioning elements, is large for the amount of metal used and is substantially uniform throughout the major portion of the casting.

It will also be apparent that the casting is a simple and economical construction to manufacture since the flanges and webs are parallel to the side walls or at right angles thereto, thus obviating the use of cores in the manufacture of the casting. Moreover, by maintaining substantially uniform section throughout the casting I avoid all checks and cracks, due to the unequal cooling of different thicknesses of metal at adjacent points.

What I claim is:—

1. A back stop casting for railway draft rigging comprising a pair of transversely extending walls connected by a web of in-

verted V-shape and having side walls 55 united to the end walls and to said connecting web.

2. A back stop casting for railway draft rigging comprising front and rear transversely extending walls connected by a longitudinally extending web of inverted V-shape and having side walls of greater depth than said end walls.

3. A back stop casting for railway draft rigging comprising an integral casting having a longitudinal cross section of substantial I-shape, and a connecting web which slopes from the longitudinal center line of the casting.

4. A back stop casting for railway draft rigging comprising a pair of transversely extending webs, one of which is concaved transversely of the draft rigging and adapted to engage the draft yoke and limit the movement thereof in one direction, said web 75 conforming in contour to the adjacent portion of the said yoke.

5. A back stop casting for railway draft rigging comprising a pair of end walls, a pair of side walls, and means for connecting 80 all of the said walls, said means comprising a web of substantially inverted V-shape, the central portion of said web intersecting one of said end walls adjacent the center line thereof.

6. A back stop casting for railway draft rigging comprising end walls, side walls, and a connecting web, said casting being substantially symmetrical, the cross sectional area of said casting at opposite ends being 85 equal.

7. A back stop casting for railway draft rigging comprising spaced end walls and spaced side walls, all of said walls being connected by a web whose elevation increases 95 from a point adjacent the side walls toward the longitudinal center line of said casting.

8. A back stop casting for railway draft rigging comprising a pair of end walls and a pair of side walls, a transversely extending web connecting all of said walls, a longitudinally disposed web connecting the said end walls and attached to said web, and additional webs joining said end walls to said web.

In testimony whereof I affix my signature.

DONALD S. BARROWS.
